UNITED STATES PATENT OFFICE.

EDWARD SCHUYLER AND CHARLES R. SEYBERT, OF SYRACUSE, NEW YORK.

COFFEE-CANISTER.

1,199,502.

Specification of Letters Patent. Patented Sept. 26, 1916.

Application filed January 8, 1916. Serial No. 71,088.

To all whom it may concern:

Be it known that we, EDWARD SCHUYLER and CHARLES R. SEYBERT, citizens of the United States, residing at Syracuse, in the county of Onondaga and State of New York, have invented certain new and useful Improvements in Coffee-Canisters, of which the following is a specification.

This invention relates to coffee canisters, and the invention relates particularly to a ground-coffee container having an attachment for measuring the coffee to be used.

The object of the invention is to provide a simple and serviceable container for ground coffee, which is detachably mounted, in an inverted position, in a suitable bracket.

A further object is to provide a detachable closure or cap for closing the mouth of the canister.

A further object is to provide a rotatable measuring device which is supported by said closure or cap, by means of which accurately measured portions of the ground coffee may be withdrawn by gravity from the canister, and then discharged into a coffee-pot, or percolator. And a further object is to provide novel resilient means for connecting the measuring device to the cap or closure of the canister.

The various features and parts of the invention will be understood from the detailed description which follows, by reference to the accompanying drawing, in which—

Figure 1 is a side-elevation of the complete device and its support. Fig. 2 is an enlarged horizontal section, taken on line 2—2 of Fig. 1. Fig. 3 is an enlarged central vertical section, taken on line 3—3 of Fig. 2, showing the resilient connection between the measuring cup or drum and the canister. Fig. 4 is a transverse vertical section, taken on line 4—4 of Fig. 2, showing the measuring cup in the position to receive the contents of the canister. Fig. 5, is a similar section showing the measuring cup operated sufficiently to discharge its contents. Fig. 6 is an isometric view of the measuring cup.

In the drawing, 2 represents the canister or container for ground coffee, tea, and the like, which may be made of glass or metal, and which is preferably inverted after being filled, as shown in Fig. 1, and detachably mounted in a bracket comprising a yoke 3,

to receive the body of the canister, and a loop 4 to receive the neck or reduced portion of the canister. The bracket 3—4 may be made out of any suitable material and in many designs, one of which, made of wire, we have illustrated in the drawing. In applying the canister to the bracket, the neck of the canister is inserted in the loop 4 and then the body is forced between the arms of the yoke 3, which hold the canister in the upright position, as shown.

5 represents a metal cap, which may be snapped or screwed on to the mouth of the canister, in the usual manner, but is preferably readily detachable for permitting the quick refilling of the container. The body of the cap 5 is perforated centrally, as at 6, by the use of a suitable punch and die, the perforation being substantially square, as shown in Fig. 2. The opening 6 in the cap is formed by shearing the metal on three sides, for producing a tongue 7, which is afterward bent outwardly substantially at right angles to the plane of the cap, and said tongue is formed into a substantially true arc for providing a guard which cooperates with the movable measuring parts.

8 represents the measuring cup or drum, which is a hollow cylindrical part, having a circumferential opening 9, by means of which the cup is filled and emptied. The cylinder 8 is disposed partway in the opening 6 of the cap, as best seen in Figs. 2, 3, 4 and 5. The cup 8 is held in place, and allowed to partially rotate, having its bearing against the opposite ends of the slot 6, and also against the hollow side of the guard 7, by a pair of coil springs 10 and 10'. One end of each spring is inserted in perforations 11 in the cap at the opposite sides of the opening 6, while the opposite ends of the springs are inserted through openings 12 which are disposed centrally in the opposite ends of the cup 8. The springs 10 and 10' are so arranged that they tend to draw and hold the cup 8 in positive engagement with the margins of the opening 6 of the cap, and yet allow the cup to be partially rotated, as from the full to the dotted line position shown in Fig. 1. From one end of the cup 8 projects a handle 13, by means of which the cup is rocked or turned during the filling and emptying operations (see Figs. 2, 4 and 5). The capacity of the cup or measuring part 8 may be varied to suit the uses to which it is put. For common house-

hold use the cups 8 are preferably made to hold the portion or amount of ground coffee, usually about a tablespoonful, allotted to each drinker.

5 To obtain the coffee from the canister 2, the operator holds a coffee-pot directly beneath the cup 8, with one hand, while with the other hand he grasps the handle 13, and rocks the cup back and forth as many times 10 as there are persons to be served. Each time the cup 8 is turned to the position shown in Figs. 1 and 4, the opening 9 in the cup is brought opposite the opening 6 in the cap, and the ground coffee or other contents of 15 the canister gravitates into the cup 8, and the turning of the cup 8 to the position shown in Fig. 5 shifts the opening 9 to the bottom side of the cup, clear of the guard 7, and the measured portion of the coffee will 20 escape by gravity from the cup 8.

Owing to the extreme simplicity of our invention it only requires a minute or two to refill the canister, and the contents, or the portion thereof required for a meal, can be 25 withdrawn in a few seconds' time, without any waste or loss. When the cup 8 is in either the closed or the open position the canister is practically air tight.

Having thus described our invention, 30 what we claim as new and desire to secure by Letters Patent, is—

1. In a measuring device for canisters, the combination with a rotatable cylindrical measuring cup having an opening to receive

the contents of the canister and a handle for 35 manipulating the said cup, of a detachable cap for closing the mouth of the canister, said cap having a central perforation and an integral arc-shaped guard depending from one margin of said perforation, said guard 40 having a curvature corresponding to that of said cup and comprising an external bearing for the cup when the latter is rotated, and means for holding said cup partway in 45 said perforation and in operative engagement with said guard.

2. The combination with a canister having its mouth facing downwardly, of a detachable cap for normally closing the mouth of the canister, said cap having a substantially 50 square perforation and a depending arc-shaped guard having a breadth equal to one side of said perforation, a rotatable measuring cup disposed partially in said perforation and having its lateral bearing in the hollow side of said guard, said cup having an opening to receive the contents of the canister and adapted to be rotated in said perforation and in said guard for discharging 55 said contents after the opening in said cup passes below the free end of said guard, and means for holding said cup in frictional contact with said cap.

In testimony whereof we affix our signatures.

EDWARD SCHUYLER.
CHARLES R. SEYBERT.
